UNITED STATES PATENT OFFICE.

THOMAS H. BROWN, JR., OF NEW YORK, N. Y.; JOHN J. P. ODELL ADMINISTRATOR OF SAID BROWN, DECEASED.

TEMPORARY BINDER.

SPECIFICATION forming part of Letters Patent No. 367,017, dated July 19, 1887.

Application filed September 6, 1880. Serial No. 16,587. (No model.)

To all whom it may concern:

Be it known that I, THOMAS H. BROWN, Jr., of New York city, and State of New York, have invented certain new and useful Improvements in Temporary Binders; and I do hereby declare that the following is a full, clear, and exact description thereof, reference being had to the accompanying drawings, and to the letters of reference marked thereon, which form a part of this specification.

This invention relates to certain novel features of construction in binders or filing receptacles for papers, which improvements are hereinafter fully set forth and claimed.

Figure 1 of the drawings illustrates my improvement applied to a temporary binder constructed with a cover for perfectly inclosing the contents, said cover, however, forming no part of the invention. Fig. 2 is a central vertical section of a temporary binder containing the improvement, the cover in this figure being absent. Figs. 3 and 4 are detailed views, which assist to show more clearly the nature of the improvement herein described.

A represents the bottom of the binder, B the back, C C the sides, and D the removable cross-bar or ledge.

I is a series of index-sheets, apertured at i, said sheets being a trifle smaller than the interior of the binder, so as to freely rise and fall between the parallel sides C C.

E is a vertical rod, attached in any suitable manner at its bottom to the binder and rising parallel with the back B through the apertures i of the index-sheets, and thereby serving to retain the index-sheets laterally in place within the binder. The upper end of said rod E, as shown in the drawings, rises through an aperture, d, in the ledge D, and above said ledge is provided with a notch or groove, n', to receive a fastening, F. By this means said rod is made to hold the ledge D from upward movement, and to thereby enable the latter to retain the index-sheets vertically in place upon the rod E, and the upper end of the rod is held in opposition to strain from the weight of the contents of the file when the latter is set upon one of its sides.

The invention relates more particularly to

the ledge D and rod and the devices for retaining said ledge removably in place.

In the use of temporary binders of this class, as is well known, papers are inserted between the unconnected index-sheets I, and when the case is filled the papers, together with the index-sheets, are removed from the binder in a mass for permanent disposition elsewhere. Heretofore I have used a fixed cross-piece or ledge at D and a removable rod. In the present instance the rod E is permanently affixed to the binder case or box and the cross-piece D is made removable to permit the withdrawal of the index-sheets from the rod, the fastening F serving to retain the cross-piece or ledge in place until it is desired to remove the contents of the binder and to insert a fresh index.

To further describe the particular construction shown in the drawings, the ends of the ledge rest in recesses c, cut in the upper surfaces of the sides C, and said ledge is provided with shoulders d', which bear outwardly against the inner surfaces of said sides C. The ledge D is obviously incapable of lateral movement while held down in place by its attachment with the rod E, as described. The fastening F is also shown in the form of a slotted hook pivoted to the ledge D in order to prevent its loss or displacement.

I do not wish to be restricted to the particular means shown for retaining the ledge D in place, for, obviously, said ledge may be hinged to the back B of the binder-case, and may be held down otherwise than by attachment with the rod E. The fastening F, if employed, may also be attached to the under surface of the ledge D, the rod in that case being notched at a suitable point below the ledge to receive the fastening thus placed.

It will be seen that the ledge D, when held laterally in place by its connection with the body of the binder and apertured to engage with the rod E, serves to hold the said rod in its vertical position and to prevent its being tilted forward by the weight of the index-sheets and papers embraced between them whenever the file is held in an inclined position, or when (in the case of a closed file) the latter is set away upon one of its ends.

The oblong holes formed in the index-sheets for the insertion of the rod E are, with respect to their form, made the subject of another application (Serial No. 108,156) for patent, filed 5 by me October 5, 1883.

I claim as my invention—

1. The combination, with a filing-receptacle and apertured index-leaves, of a rod attached at its lower end to the receptacle and a support upon the receptacle detachably engaged with the upper end of the rod and adapted to hold the latter from lateral movement, substantially as and for the purpose set forth.
2. The combination, with a receptacle and apertured index-leaves, of a rod attached at its lower end to the receptacle, an upwardly-movable ledge laterally supported by its connection with the receptacle, and a fastening device for detachably connecting the upper end 20 of the rod with the ledge, substantially as and for the purpose set forth.
3. The combination, with a receptacle and apertured index-leaves, of a rod attached at its lower end to the receptacle, an upwardly-mov-

able ledge supported upon the receptacle and laterally supported by its connection with the receptacle and apertured to receive the upper end of the rod, and a fastening device adapted to retain the ledge vertically in place upon the rod, substantially as and for the purpose set forth.

4. The combination, with a receptacle for papers and apertured index-leaves, of a rod attached at its lower end to the receptacle and notched at its upper end, an upwardly-movable ledge laterally supported by its connection with the receptacle, and a fastening device constructed to engage the notched upper end of the rod and adapted to hold the ledge vertically in place upon the rod, substantially as and for the purpose set forth.

In testimony that I claim the foregoing as my invention I affix my signature in presence of two witnesses.

THOS. H. BROWN, JR.
